VACUUM STRIP RETENTION

Frank Edwin Stirn, Pearl River, and Arthur Sinclair Taylor, Spring Valley, N. Y., assignors to American Cyanamid Company, New York, N. Y., a corporation of Maine

Application November 3, 1950, Serial No. 193,946

3 Claims. (Cl. 53—10.5)

This invention relates to improvements in a method and mechanisms for forming and filling capsules from soft elastic strip material such as gelatin, which capsules may be filled with any desired material, and relates particularly to a method of retaining the strip on the surface of the die, in such fashion as to avoid slippage and to prevent variations in size of the capsule and to permit the obtaining of straight, evenly-formed capsules.

In the past, it has been found that in standard capsulizing machines, in which a gelatin film is held against the surface of a die roll, the vacuum to force the gelatin strip down into the individual cavities on the die roll for the formation of capsules has been applied solely to the area in which it was desired to cause the gelatin film to be pressed downward or held against the die roll. Also, it has been customary to use a certain amount of lubrication to prevent the gelatin strip from adhering to the die roll and to make it easier to handle. As a result of these combined actions, capsules have been produced but all too frequently there has been a previously unexplained variation in the size and also an unexplained irregularity in shape, particularly in the long cylindrical form of capsules with rounded ends referred to in the trade as "flat ovals." They frequently have had a heliform or worm-shape; they have come out with various types of configurations like a kidney bean or a jelly bean, rather than a straight, symmetrical, evenly-formed capsule as is desired.

We have found that these irregularities result from the skidding of the gelatin on the surface of the die roll during its formation into the capsules. Surprisingly, we have found that by the use of a vacuum on both the inside and the outside of the capsule forming cavities, it is possible to draw the gelatin film towards the surface of the die roll, both inside and outside of the cutting-out edges and both inside and outside of the capsule-forming cavities, and thereby provide a means whereby the gelatin film, being more evenly retained, does not tend to skid or slide in and out of the capsule-forming cavities, nor otherwise on the roll, and accordingly, it is evenly and symmetrically held in position. The strip is normally thus held during the filling and up until the time of sealing or cut-out. The capsules, when formed, also develop an even, symmetrical and uniform configuration.

We have found that by varying the relative internal and external tensions and the exact moment of application of the various vacuums, it is possible to obtain a variation in the size of the capsules formed with a particular size of die. This is most desirable in the pharmaceutical profession because it is frequently found that the strength of the encapsulated material may vary from batch to batch, or various materials are to be used which give a variation in the size of the capsules. To avoid an unnecessary large inventory of capsulizing dies, it is highly desirable that more than one size may be formed from a single die roll. In the past, a variation in strip thickness has been used, as for example by Weckesser 2,323,582. Such a system uses more gelatin, and the variation in wall thickness gives an undesirable lack of uniformity in the product.

We have found it desirable in the formation of capsulizing dies to leave or form small grooves or vents between the cavity die insert and the main body of the roll, whereby the vacuum which operates inside the gelatin cavity operates also outside the cavity.

For greater flexibility, it is desirable that separate vacuum hold-down connections or bleed passages be used

2

to the inside and the outside of the capsule-forming cavities, whereby it is possible to control the vacuum independently.

For large production runs, where but a single capsule size is desired, and a uniformity of composition of the filling contents is to be expected, it is possible to use but a single manifold system with air leads to both the inside and the outside of the cavity ledge, and thereby attain satisfactory results with a more easily formed capsulizing die.

10 Our method of retaining the strip in position is of particular value if the strip is coated on what is to become the inside of the capsule with an adhesive material such as a silicone resin or gum benzoin, or shellac, etc. If such a coating is used, it is desirable that none of the feeding or forming mechanisms contact the strip after the coating is applied. Our method of strip retention is particularly useful under such circumstances.

Our new type of hold-down dies may be used to position the strip in capsulizing machines like those shown in 20 our co-pending application Serial No. 164,426 filed May 26, 1950 for use with a single die roll against the flat sealing roll.

Our vacuum strip hold-down may be used in machines 25 like those shown by Scherer 1,970,396 to retain the strip in position while the capsule cavities are being formed. Our vacuum strip hold-down may be used also in machines like those shown in Weckesser 2,323,581 and those shown by Cowley 2,387,747. Such machines are double-sided and vacuum strip retention is preferably to be used 30 on each roll.

Our vacuum strip retention may also be used for submerged filling like that shown by Pittenger 2,219,578 and 35 may be used with either the double roller or the roll and flat die form shown by him.

35 Other modifications for use with other machines will be obvious to those skilled in the art.

Having thus described certain advantages thereof, certain modifications of our invention are shown in detail by the following drawings.

40 Figure 1 is a surface view of a capsule die roll for flat oval capsules.

Figure 2 is a sectional view along line 2—2 of Figure 1 showing the manifold passages.

Figure 3 is a modification of our invention showing 45 round capsule dies.

Figure 4 is a modification of our invention showing a separate vacuum system for the hold-down.

Figure 5 is a sectional view along line 5—5 of Figure 4 showing a manifold system for use with separate hold-down ducts, showing the strip with the retention vacuum applied, before the application of the capsule cavity-forming vacuum.

55 In Figure 1 there is shown a cavity die roll 11 having in its surface capsule cavity inserts 12. These inserts may be a press fit in insert slots 13. Each of the capsule cavity inserts has a cutting out rim 14 over which a deformable strip material 15 is placed. Normally a soft gelatin film is preferred for capsule work; various substitutes for gelatin may be used for this strip. Under the 60 capsule cavity inserts, there may be a capsule ejector piston cylinder 16 in which fits a capsule ejector piston 17 to which is attached a capsule ejector plug 18. To the cylinder 16 is connected a manifold 19 which connects the cylinders with a valve seat surface 20 of the cavity die roll. 65 On this surface rests a valve plate 21 in which there is a vacuum chest 22 to which a vacuum connection 23 is attached. This general form of die roll is described in our earlier applications, Serial Nos. 164,426 and 174,748.

70 A restricted passage 24 serves as a vacuum bleed during the forming cycle of capsulizing operations. This passage should be very small, but in the drawings is accentuated so as to be visible. A partial vacuum applied through the vacuum connection to the vacuum chest, in turn through the manifold 19, past the capsule ejector piston and plug and hence to the cavity die underneath the strip material, holds the strip material against the surface of the cutting out rim and pulls this deformable strip material down into the capsule cavity preparatory to its being filled.

75 In the past the strip material has skidded on the surface

of the capsule cavity insert and has accordingly permitted a variable amount of the strip material to slide into the capsule cavity. Previously, this movement of the film over the die rim has been considered to be an advantage. Note for example, column 1, lines 20-25 of the patent to Cowley 2,387,747. We have found that the irregularities in this skidding causes irregularities in the capsule. Our restricted passage, or vacuum bleed, permits the vacuum to operate outside of the capsule die insert and outside of the cutting out rim and hold the gelatin film towards the surface of the cavity die roll as is shown in Figure 2. It is important that the vacuum bleed be of such size as to not admit enough air to break the vacuum or overtax the capacity of the passages and yet at the same time, it is necessary that it be sufficiently large to be effective. As the gelatin film feeds towards the surface of the cavity die roll, it has the tendency to lay flat on the surfaces of the rims and must be pulled down into contact with the die roll both inside and outside of the cavities by the reduction of pressure under the strip. It is desirable that the passages be of such size as to give a reduced pressure zone over the entire arc of contact, and particularly at the point of actual fill.

The exact size and shape of this vacuum bleed passage may vary over a wide range depending upon its relationship with the other elements present, the capacity of the vacuum pump, etc.

From the above description, to those skilled in the art the relative proportions required will be obvious. By way of example, it has been found that with a flat oval cavity which is $1\frac{1}{22}$ " wide and whose end centers are .682" apart that a vacuum bleed formed by a $\frac{1}{8}$ " diameter end mill cutting a slot 0.20" deep into the end of the slot and .003" below the bottom of the insert slot forms a very effective vacuum bleed. A $\frac{1}{8}$ " manifold passage leading to a valve plate with a vacuum chest 0.2" wide and 0.15" deep connected to a $\frac{1}{8}$ " pipe tap as a vacuum connection is a desirable arrangement. Multitudinous variations from these particular sizes are possible, as above mentioned.

It is also convenient when forming the insert slots to form them slightly longer than required for the capsule cavity insert and then nick one end at the bottom to provide the vacuum bleed.

An independent hole to the surface of the cavity die roll from the manifold passage 19 may be used. For this purpose a #44 drill gives a proper size of bleed for the particular size capsule mentioned above.

The embodiment shown in Figures 4 and 5 has a separate vacuum bleed 25 leading to a bleed port passage 26 which leads to the valve seat surface adjacent a separate bleed vacuum chest 27 in the valve plate to which is connected a separate bleed vacuum connection 28. In Figure 5 the gelatin strip is shown with the holding vacuum applied; thus retaining the strip in position, but before the shell forming vacuum is applied, hence the gelatin strip is not yet pulled into the capsule cavity to form the capsule shell. This modification is of particular advantage when it is desired to vary the size of the capsule formed by a particular die roll.

The separate vacuum chest and passages permit the holding vacuum to be independently applied, prior to, simultaneously with, or subsequent to the capsule shell forming vacuum in the cavity die inserts. With a single vacuum chest, and a single manifold system, the capsule shell forming vacuum which pulls the gelatin strip into the capsule cavity is simultaneous with the strip hold-down vacuum.

It is not necessary that a bleed passage be adjacent to each capsule forming cavity cutting out rim. As shown in Figure 3, the vacuum bleeds may be present adjacent only certain of the rows of the cavities or, may be present at alternate cavities in alternate rows, or as desired. It is possible to obtain a proper vacuum by using fewer bleed passages and making them slightly larger.

It will also be obvious that the bleed passages can be formed in die rolls formed from a single metal blank as well as those of built-up construction.

A variation in the bleed vacuum applied through the bleed vacuum connection can increase or decrease the holding action on the strip material outside of the capsule cavity inserts and therefore influences the tension of the gelatin film in the capsule cavity inserts, and this in turn permits a variation in the size of the capsules formed. An increase in this bleed vacuum decreases the diameter of the capsule. To those skilled in capsule making procedures, this modification which permits a variation in the size of the capsule with a single cavity die roll will appear of greatest value. The die rolls cost several hundred dollars and previously had to be manufactured separately for every minute variation in size of finished capsule. Modifications in the particular size and shape of the bleed passages will of course, be obvious to those skilled in the art.

Having described certain modifications thereof, as our invention we claim:

1. The method of retaining a soft elastic strip adjacent to the surface of a capsule die roll, which comprises placing the strip adjacent the surface of the die roll and reducing the pressure in capsule cavities in the die roll surface, thereby forming pockets in the strip, and independently and separately controllably reducing the pressure under the portion of the strip outside of the capsule cavities, thereby retaining the strip in position.
2. The method of forming soft elastic capsules from a soft elastic strip which comprises uniformly and continuously feeding at least one strip of elastic strip adjacent to a capsule die roll surface which has thereon a plurality of capsule-forming cavities, each of which has a cutting out rim, sequentially reducing the pressure within a series of said capsule-forming cavities, thereby causing the elastic strip material to form shells within the cavities and independently and separately controllably reducing the pressure under the portion of the strip outside of the capsule cavities, thereby holding the elastic strip down to and adjacent the die roll surface, thereby preventing the slipping of the strip material on the cutting out rims, placing capsule contents serially in the thus formed shells, placing a second layer of elastic strip adjacent the first strip and cutting out and sealing capsules from the thus filled shells.
3. A die roll for forming soft elastic capsules from an elastic strip which comprises a cylindrical die roll blank, in the cylindrical periphery thereof, a series of capsule-forming cavities each consisting of a raised rim insert fitted into the periphery of said cylindrical roll, and in a recess under said insert at least one ejector plug, said ejector plug having thereon a piston head, whereby said plug may be, by air pressure, raised to substantially the top of said cavity, a piston cylinder, a manifolding passage from an end of said cylinder to a valve surface of said roll, sufficient clearance between the piston and the plug that any variation in pressure within said manifold passage is permitted to communicate itself around the plug and the piston into the capsule forming cavity, and a second manifolding passage from a valve surface of said roll to a location on the cylindrical surface of the die roll blank which is outside of the capsule forming cavities, whereby pressure between the elastic strip and the die roll blank but outside of the capsule forming cavities may be independently controlled.
